J. H. SNYDER.

Making Railroad Chairs.

No. 20,901.

Patented July 13, 1858.

Inventor
John H. Grayson

UNITED STATES PATENT OFFICE.

J. H. SNYDER, OF TROY, NEW YORK.

ROLLING RAILWAY-CHAIR.

Specification forming part of Letters Patent No. 20,901, dated July 13, 1858; Reissued June 3, 1862, No. 1,316.

To all whom it may concern:

Be it known that I, JOHN H. SNYDER, of the city of Troy, in the county of Rensselaer and State of New York, have invented a new and useful Improvement in Manufacturing Wrought-Iron Railway-Chairs of the Kind Hereinafter Described; and I do hereby declare that the following is a full and exact description of the same, reference being had to the annexed drawings, making a part of this specification, in which the same letters indicate like parts in all the figures.

In the annexed drawings, Figures 1 and 2 are perspective views of the chairs, in the rolling of which I have made this improvement. Fig. 1 represents the chair with one inward-turned lip, A, to hold one side of the base of the rail, and with an upright flange, B, to support the other side; and Fig. 2 shows the chair with two lips A, A, turned inward. In each chair the lip and flange, or the two lips, extend the whole length of the chair, and the bottom of each chair projects out on both sides, as at C C, beyond the bases of the lip and flange or the two lips, throughout their whole length. Figs. 1 and 2 represent the chairs as they appear when shaped and made of proper length, but before they are punched to receive the spikes 30 which are to hold them to the timbers of the track. Fig. 3 is a perspective view and Figs. 4 and 5 are transverse sections of the blank from which I make the chairs with one lip A; and Fig. 6 is a perspective view 35 and Fig. 7 a transverse section of the blank from which I form the chairs with two inward-turned lips. Wrought-iron railway-chairs, having the same general construction as these, have been heretofore produced 40 from substantially the same blanks as those from which I manufacture these chairs.

My improvement relates only to the mode of forming or turning inward the lip or lips of the chairs. 45 I form or turn inward the lip or lips A of the chairs by means of two suitably shaped rollers D, E, mounted and run together in the same manner that rollers are commonly set and run together in rolling iron. The 50 arrows on the rollers indicate their direction of motion. F, Fig. 8, represents a section of the frame which holds the rollers; and G G are the usual set-screws by which the upper roller is adjusted to and kept from receding too far from the lower one. These

rollers are provided with front guide-plates and back guard-plates, (not shown in the drawings,) corresponding respectively in form to the blanks, and the bars of chairs produced, the same as rollers for forming other iron bars of irregular shape are usually furnished with.

In manufacturing the chairs which have but one lip A, from the blanks Fig. 3, I run each blank, while at a welding heat or thereabout, edgewise between the rollers D, E, through the grooves P and N as shown at I in Figs. 8 and 9. There the roller E has the collar O, upon which collar the flange H of the blank is drawn and turned down by the side c of the groove P in the roller D, so as to form the lip or give the blank the shape there shown in cross section, or at Fig. 10 in perspective. The groove N in the roller E is shaped to fit the flange-edge of the blank, and keep it in place while running through between the rollers, as shown. After the blank has been passed through the grooves P and N, it is then immediately run flatwise between the rollers in the grooves U and V, as shown at J in Figs. 8 and 9;—which grooves are so shaped that when the blank leaves them the bending of the lip of the chair is completed, as there shown in cross section, and at Figs. 14 and 15 in perspective.

In forming the chairs with two lips, A, A, from blanks like that seen in Fig. 6, I run each blank, while at a welding heat or thereabout, twice, edgewise, between the two rollers, D, E, Fig. 12;—once, as shown at R, to turn one lip, and again, as represented at S, to form the other; the roller E there having the collar O, O, upon which the flanges H, H, of the blank are drawn down and turned inward by the sides c c of the grooves P, P, in the roller D, so as to form the lips or give the blank the shape shown in cross section at S. The roller E also has the grooves N, N, formed to fit and keep in place that edge of the bar not being acted upon by the roller D and collar O. This twice running of the blank edgewise between the rollers so prepares it that it afterward receives the required form of the chairs by passing it flatwise between the two rollers shaped and run together substantially as shown at T in Fig. 12. Fig. 13 is a perspective view of a finished bar of the chairs as left by the rollers at T.

After the bars have received the form of the chairs, as shown by Figs. 13, 14 and 15, the bars are then immediately sawed into the required lengths, Q, for the chairs, as indicated by the transverse lines α , and afterward punched in the usual manner with holes, w , for the spikes.

The form of the collar or collars O will vary according to the shape of the recess 10 to be left under the lip or lips of the chairs, as shown by Figs. 8 and 9; and the form of the grooves N P and U V, will also be different as the shape of the lip or lips A and flange B varies, as illustrated in Figs. 8, 9 15 and 12.

Now, in manufacturing wrought-iron railway-chairs of the kind herein described, from blank bars having two upright flanges H B, or H, H, substantially as represented 20 in Figs. 3 and 6, my improved mode of forming or turning inward the lip or lips A of the chairs, may be distinguished from every other method of doing the same thing, by the fact that in my mode the lip or lips, 25 A, of the chairs are formed or turned inward upon a collar, (or collars,) O, of a roller, E, by means of another roller D, substantially as herein set forth. This mode of turning inward the lip or lips of the chairs 30 upon the collar or collars of a roller constitutes my invention, and is much better than the methods heretofore practiced, by myself

and others, of forming the lip or lips of the chairs upon a stationary core, or mandrel, or former, fixed between two rollers which 35 draw the blank along and work the flange or flanges H in upon the core. For it is difficult to keep the core in its place between the rollers, especially in forming the chairs with one lip; and the core heats rapidly 40 and quickly wears down so as to leave the chairs too narrow to receive the rails; and hence the cores must be often renewed. And the core is an obstruction to the introduction of the blank between the drawing rollers above and below the core; and the blank 45 is drawn along the core or former with much difficulty. Besides, the chairs are manufactured at a much cheaper rate, and are also better, when their lips, A, are 50 turned upon the collar O of the roller according to my mode herein described, than when the lips of the chairs are formed upon a core as heretofore practiced.

What I claim as my invention and desire 55 to secure by Letters Patent is—

Forming or turning the lip, or lips, A, of the chairs, upon the collar, or collars, O, of a roller, E, by means of another roller, D, substantially as herein set forth.

JOHN H. SNYDER.
